HAIR CURLER

John Parrilla, Brooklyn, N. Y.

Application March 2, 1951, Serial No. 213,647

8 Claims. (Cl. 132—33)

1

This invention relates to hair curlers, and more particularly to curlers of the type having rigid slotted bodies adapted to receive strands of hair whereby the hair may be twisted about the bodies.

Various types of rigid-body hair curlers have been proposed and produced in the past. One type comprises a simple elongate member having a hand-grip portion and a curling portion provided with a slot for receiving the strands of hair. In the operation of this hair curler, the hair ends are inserted in the slot and then the curler is turned to cause the hair to be twisted about the slotted body portion of the curler. The curler is then removed and a bobby pin or other suitable device is applied to the curl to enable it to remain its shape.

Another type of rigid-body hair curler consists of an elongate member having a central hand-grip portion, and having slotted end portions of different diameter disposed on opposite sides of the hand-grip portion whereby curls of different sizes may be formed.

In the operation of these prior curlers quite some skill was required to maintain the strands of hair in the slot prior to and during the operation of twisting the hair about the curler. Not only did this operation require skill, but it also necessitated the use of two hands most of the time.

The above disadvantages of these prior curlers are obviated by the present invention, and an object of the invention is to provide an improved rigid-body, slot-type hair curler which requires less skill in its operation than the prior devices, and which does not require constant use of both hands during the curling operation.

Another object of the invention is to provide an improved hair curler as above set forth, which is small in size and compact, and light in weight.

A still further object of the invention is to provide an improved hair curler according to the foregoing, which is simple in construction and economical to fabricate.

Yet another object of the invention is to provide an improved hair curler as above set forth, which is simple and easy to operate, even for an inexperienced person.

In accomplishing the above objects I provide a novel hair curler comprising an elongate structure having a hand-grip portion, and having a curling portion provided with a hair-receiving longitudinal slot extending to one end of the structure. I also provide resilient means extending in the slot of the structure for engaging and

2

holding strands of hair inserted in the slot, for the purpose of twisting the hair around the structure. The said resilient means is preferably in the form of an elongate leaf spring, and may be of wire or of flat strip stock.

In one specific illustrated form of the invention the hair curler has two curling portions of different diameters, connected by an intermediate hand-grip portion. In this construction both of the curling portions may be provided with resilient springs for gripping the hair inserted in the slot thereof, and said springs may be formed integral with each other, of a single piece of wire or metal.

15 As will hereinafter be brought out in detail I provide a novel organization whereby the springs may be economically mass-produced and quickly and easily assembled to the curling member by production methods to minimize the cost of the curler.

20 Other features and advantages will herein-after appear.

In the accompanying drawings:

25 Figure 1 is a side elevational view of an improved hair curler made in accordance with the invention.

Fig. 2 is a longitudinal sectional view taken through the hair curler of Fig. 1.

Fig. 3 is an end view of the curler, enlarged.

30 Fig. 4 is a transverse section taken on line 4—4 of Fig. 2.

Fig. 5 is a cross sectional view of a curling portion of the curler, showing strands of hair held in place by the leaf spring.

35 Fig. 6 is a side elevational view of a modified form of curler, as provided by the invention.

Fig. 7 is a longitudinal sectional view of the curler shown in Fig. 6.

Fig. 8 is a view partly in elevation and partly in section of a curler illustrating still another form of the invention.

The improved hair curler shown in Figs. 1 through 5 comprises an elongate structure generally designated by the numeral 10, having a knurled central hand-grip portion 11 and having curling portions 12 and 13 respectively disposed on opposite sides of the hand-grip portion 11. The structure 10 is generally cylindrical in shape, and as shown the curling portion 13 is made of smaller diameter than the portions 11 and 12.

The curling portions 12 and 13 are provided with hair-receiving longitudinal slots 14 and 15 respectively, extending from their ends to points 55 closely adjacent the hand-grip portion 10.

In accordance with the present invention, novel resilient means are provided, extending in the slots 14 and 15 of the curler for engaging and yieldably holding strands of hair which are inserted. By the provision of such means, which is preferably constituted of a leaf spring, the operation of curling the hair is greatly simplified and made easier, requiring much less skill on the part of the operator. Moreover, such resilient means enables the curling operation to be done partly with one hand, freeing the other hand and therefore further adding to the convenience of the device.

Accordingly, as shown in Fig. 2, the structure 10 may comprise elongate members 16 and 17 constituting halves which may be substantially identical with each other, said halves having flat sides disposed in broadside relation with portions spaced apart to form the slots 14 and 15.

Interposed between the members 16 and 17 is an elongate leaf spring having a central base portion 18, and having hair engaging end portions 19 and 20, the latter being disposed in the slots 14 and 15 respectively.

The member 17 may have cuts 21 and 22 in its ends, to accommodate bent ends 23 and 24 of the leaf spring, whereby insertion of the strands of hair is facilitated, inasmuch as the hair will not be caught on the ends of the leaf spring. The spring portions 19 and 20 have offsets 25 and 26 which serve to correctly position the spring during assembly of the curling structure, and which provide for a softer spring action adjacent the inner ends of the slots 14 and 15.

Referring to Figs. 2 and 4, the member 16 and 17 are held in assembled relation by a ring or annulus 27 which may be pressfitted in place and may constitute the hand-grip portion 11 of the structure 10. The member 16 may have recesses 28 and the member 17 projections 29 receivable in the recesses 28 to key the members together.

The operation of the curling structure is as follows: Strands of hair 30 as shown in Fig. 5 are inserted in one or the other of the slots 14, 15 whereupon they will be yieldably held in place by the spring portions 19 or 20. The curler is then turned as indicated by the arrow in Fig. 5, causing the hair to be curled about the slotted curler portion, forming a curl. The curler is then withdrawn while the curl is held in place, whereupon a bobby pin or other suitable means may be employed, to maintain the shape of the curl.

The provision of the leaf springs greatly facilitate the curling operation in that they retain the hair in the slots and enable the curling operation to be carried out without as much skill or care as was formerly required.

Also the provision of the spring speeds up the curling operation and enables an operator to have one hand free part of the time, whereas previously, two hands were required most of the time.

Another form of hair curler made in accordance with the invention is shown in Figs. 6 and 7. This hair curler comprises an elongate member 31 having a central knurled hand-grip portion 32 and having curling portions 33 and 34 disposed on opposite ends of the hand-grip portion 32. The curling portions 33 and 34 have open ended slots 35 and 36 for receiving hair which is to be curled, and have other slots 37 and 38 provided with closed ends, through which slots there extends an elongate leaf spring 39.

The spring 39 has a base portion 40 received in a cut or groove 41 in the hand-grip portion 32.

of the member 31 where it is secured in place by swaging the edges of the cut, as indicated at 42, Fig. 6. The spring 39 has hair-engaging end portions 43 disposed in the slots 35 and 36, and the ends of the spring portions 43 are bent and retained in the slots 37 and 38 to prevent hair from being caught on said ends.

Operation of the curler shown in Figs. 6 and 7 is the same as that described above in connection with the curler structure 10.

Yet another form of the invention is shown in Fig. 8. In this figure the curler structure 31a is generally the same as the structure 31 shown in Figs. 6 and 7. However, the hand-grip portion of the curler structure 32a is constituted of a sleeve or annulus 44 which is pressfitted over the central portion of the curler structure 31a, retaining the leaf spring 39 in assembled relation to the curler. To accommodate the sleeve 44 the central portion 32b of the member 31a is slightly reduced in diameter.

Variations and modifications may be made within the scope of the claims and portions of the improvements may be used without others.

I claim:

1. A hair curler comprising an elongate structure having a hand-grip portion, and having a curling portion provided with a hair-receiving longitudinal slot extending to one end of the structure, at least one side of said slot having a substantially flat surface substantially equal in width to the diameter of said curling portion, said curling portion having a recess located adjacent its slotted end in the surface comprising the other side of the slot; and resilient means extending in said slot, constructed and arranged to normally press against the said flat surface, for engaging and yieldably holding in the slot strands of hair inserted for the purpose of curling said hair around the structure, said resilient means comprising an elongate spring blade having one end disposed in the said recess of the slotted curling portion.

2. A hair curler comprising a pair of elongate coextensive members having flat sides disposed broadside to each other and having exposed, opposite, convex sides, portions of said flat sides being spaced to provide a longitudinal hair-receiving slot, one of said members having a recess in its flat side adjacent the end of the slot; and resilient means comprising a leaf spring extending in said slot, for engaging and yieldably holding strands of hair inserted for the purpose of curling said hair, said spring having a base portion extending between and secured by the flat sides of the members and having an end remote from its base portion, disposed in said recess.

3. A hair curler comprising an elongate structure having a hand-grip portion intermediate its ends, and having curling portions disposed on opposite sides of said hand-grip portion and provided with hair-receiving longitudinal slots extending to their ends, said slots on at least one side each having substantially flat surfaces substantially equal in width to the diameters of said curling portions, said curling portions having recesses located adjacent their slotted ends in the surfaces comprising the other sides of the slots; and resilient means extending in said slots, constructed and arranged to normally press against the said flat surfaces, for engaging and yieldably holding in the slots strands of hair inserted for the purpose of curling said hair around the structure, said resilient means comprising a single

continuous strip of spring material extending through said hand-grip portion, having ends disposed in said recesses.

4. A hair curler comprising an elongate structure having a hand-grip portion, and having a curling portion provided with a hair-receiving longitudinal slot extending to one end of the structure, said curling portion having a recess adjacent its free end, in one face of the slot; and resilient means extending in said slot for engaging and yieldably holding in the slot strands of hair inserted for the purpose of curling said hair around the structure, said structure being divided along a longitudinal line and being formed of two halves, and said resilient means comprising a leaf spring extending between and secured by the halves of the structure along the line of separation thereof at the hand-grip portion, the unsecured end of the spring being disposed in the said recess.

5. A hair curler comprising an elongate structure having a hand-grip portion, and having a curling portion provided with a hair-receiving longitudinal slot extending to one end of the structure; and resilient means extending in said slot for engaging and yieldably holding in the slot strands of hair inserted for the purpose of curling said hair around the structure, the curling portion of said structure having a cut communicating and substantially coextensive with the hair-receiving slot, and said resilient means comprising a spring passing through said cut, said spring being secured to the hand-grip portion of the structure and having a free end disposed in said cut.

6. A hair curler comprising an elongate structure having a hand-grip portion, and having a curling portion provided with a hair-receiving longitudinal slot extending to one end of the structure; and resilient means extending in said slot for engaging and yieldably holding in the slot strands of hair inserted for the purpose of curling said hair around the structure, the hand-grip and curling portions of the structure having a common longitudinal cut communicating with the hair-receiving slot, and said resilient means comprising a spring disposed in a part of said cut, said spring being retained in place by swaged portions of the edges of the cut.

7. A hair curler comprising an elongate structure having a hand-grip portion intermediate its ends, and having curling portions disposed on opposite sides of said hand-grip portion and provided with hair-receiving longitudinal slots extending to their ends; and resilient means extending in said slots for engaging and yieldably holding in the slots strands of hair inserted for the purpose of curling said hair around the structure, said structure having an exterior longitudinal cut in the hand-grip and curling portions, said resilient means comprising a single continuous leaf spring extending through the hand-grip portion, said spring being disposed in said cut, and said hand-grip portion being swaged over the spring to retain it in place.

8. A hair curler comprising an elongate structure having a hand-grip portion intermediate its ends, and having curling portions disposed on opposite sides of said hand-grip portion and provided with hair-receiving longitudinal slots extending to their ends; and resilient means extending in said slots for engaging and yieldably holding in the slots strands of hair inserted for the purpose of curling said hair around the structure, said structure having a longitudinal cut in the hand-grip and curling portions, said resilient means comprising a single continuous leaf spring extending in and along the cut; and an annulus extending around the hand-grip portion, engaging and securing the spring in place.
